UNITED STATES PATENT OFFICE.

JOHN F. MALTHANER, OF ATLANTA, GEORGIA.

COMBINED TELEPHONE AND PHONOGRAPH.

1,323,710.

Specification of Letters Patent.

Patented Dec. 2, 1919.

Application filed December 12, 1914. Serial No. 876,864.

To all whom it may concern:

Be it known that I, JOHN F. MALTHANER, a citizen of the United States of America, and resident of Atlanta, in the counties of Fulton and De Kalb, State of Georgia, have invented certain new and useful Improvements in Combined Telephones and Phonographs, of which the following is a specification.

10 My invention relates to a combined telephone and phonograph and has for its principal object to provide a means whereby telephone conversations may be recorded upon a record cylinder of a commercial dictating machine, a further object of the invention being to so arrange the electrical circuits that under ordinary dictating conditions, certain parts of the apparatus used for receiving and transmitting telephone 20 messages may be used by the dictator.

In setting forth my invention, I only deem it necessary to show the essential features of the dictating machine equipped with my improvement. The mechanism illustrated 25 includes a standard common battery desk telephone equipment connected in circuit with an electro-magnet located on a standard Edison dictating machine, the dictating machine being slightly modified to be operated by the electro-magnet.

30 In order to avoid any objections of telephone companies due to the fact that the dictating machine is connected to the telephone circuit, one of the principal objects 35 of this invention is to provide means for obtaining a record of the telephone conversations without actually mechanically or electrically connecting the electric devices of the recording mechanism with the commercial 40 company's lines.

Another object is to modify the construction of the magnetic recorder so that it will respond quickly to the slight variations on the surface of the phonographic record and 45 to prevent accumulations from interfering with the proper operation of the diaphragm.

The above and other objects and the novel features of my invention will be apparent from the following description, taken in 50 connection with the accompanying drawings, in which:

Figure 1 is a diagrammatic representation of so much of a recording mechanism as is necessary to show my invention applied 55 thereto, and illustrating the circuits and manner of deriving the communication

from the commercial telephone company's lines;

Fig. 2 is a plan view and Fig. 3 is a central longitudinal sectional view of the 60 special telephone instrument capable of receiving a message from the telephone company's lines and also capable of use as the mouth piece for direct dictation;

Fig. 4 is an underside perspective view of 65 a cover used in the instrument shown in Figs. 2 and 3;

Fig. 5 is a central longitudinal sectional view of a magnetic recorder;

Fig. 6 is a bottom plan view of the mag- 70 netic recorder;

Fig. 7 is a transverse sectional view taken along the line 7—7 of Fig. 5, looking in the direction of the arrows;

Fig. 8 is a bottom plan view of the coun- 75 ter-weight and associated spring; and

Fig. 9 is a perspective view of a felt washer located between the reed armature and the electro-magnet.

Referring to the drawings, and more par- 80 ticularly to Fig. 1, I have illustrated only so much of a standard Edison dictating machine as is necessary to show the application of the invention thereto. A cylindri- 85 cal record receiving medium 10 is fixed on a suitable mandrel which rotates with the shaft 11. The shaft 11 is slideable lengthwise of the mandrel and has a clutch disk 12 fixed thereon provided with teeth that are capable of engaging corresponding teeth on the hub 13 of a drive wheel 14, connected by a belt 15 with a motor 16 which is mounted in any suitable position, as on the underside of a table 17.

The shaft 11 is moved lengthwise into and 95 out of clutch with the motor driven wheel 14 by means of a lever 18 pivoted at 19 on the table 17 and connected to the shaft 11 by a yoke 20. The lever 18 is rocked on the pivot 19 by an arm 21 which is connected to the lever 18 by a rod 22. The arm 21 is fixed on a short shaft 23 which is oscillated by a rockable member 24 also fixed on the shaft 23. The rockable member 24 has the two oppositely extending arms 25 and 26 at 105 its upper end which are located directly below the shanks of the buttons 27 and 28. The buttons 27 and 28 are respectively the "stop" and "start" buttons of the machine and their shanks extend through the table 110 17, engaging the arms 25 and 26 respectively and by the connections between the member

24 and the lever 18 the clutch members 12 and 13 are thrown into and out of engagement.

An additional means for operating the 5 clutch mechanism is provided and consists of an air bulb 29 mounted on a plate 30 and usually set on the floor where it can be operated by the foot of the dictator. The bulb 29 is connected by a flexible tube 31 with 10 one end of a cylinder 32. A plunger 33 works in the cylinder 32 and has connected thereto a rod 34, the opposite end of which is pivotally connected to the member 24 between the arms 25 and 26. It will be evident 15 that when the bulb 29 is pressed, air entering the cylinder 32 will force the plunger 33 outwardly and move the arm 24 to the right as shown in Fig. 1, and throw in the clutch, which will start the rotation of the 20 record receiving cylinder. A similar movement of the arm 24 may be accomplished by depressing the "start" button 28. A release 25 of the bulb 29 permits the air to escape from the cylinder 32 and the plunger 33 will return to its initial position, which movement will throw the arm 24 to the left and throw out the clutch, stopping the rotation of the record receiving cylinder. A similar movement to the left of the arm 24 may be manually effected by depressing the "stop" button 27.

An auxiliary cylinder 35 is mounted on the underside of the main air cylinder 32 and may be applied to the cylinder 32 by 35 merely boring and threading a hole in the underside of the pump cylinder 32 and connecting the two cylinders by a nipple 36. A plunger 37 works in the cylinder 35 and at its outer end carries an arm 38 having a hard rubber head 39 which is adapted to engage an inclined portion 40 at the end of a contact spring 41. It will be evident that as the plunger 38 and head 40 are moved outwardly by the air which is forced into the 45 cylinder 35 from the cylinder 32, the outer free end of the spring 41 will move downwardly into and make contact with the end of the spring 42. Both springs 41 and 42 are secured at one end to an insulating block 43, which is mounted on the underside of the cylinder 35. The foregoing auxiliary cylinder 35 and the appliances connected therewith are so constructed that they 50 may be applied to the cylinder 32 as a unit and are described in detail in the pending application heretofore referred to.

The usual frame for the recording and reproducing instruments of the standard Edison dictating phonograph is utilized and 55 comprises a spectacle frame 44, which is pivotally mounted on the upper horizontal bar 45. The frame 44 is also pivoted so as to swing substantially horizontally or in its own plane to bring either the recorder or 60 reproducer into a position where the stylus

thereof may engage the surface of the record cylinder 10. The reproducer of the machine is not changed and is identical with that of the standard machine.

Referring to Figs. 5 to 9 inclusive, the 70 magnetic recorder embodying our invention comprises a stationary hollow casing or head 46 which has a flange 47 capable of supporting it within one of the openings of the spectacle frame 44. The upper end of the casing 46 is closed by a screw cap 48 and the lower edge has a lug or ear 49, depending therefrom. The outer end of the lug or ear 49 is perforated to receive a pin 50, whereby the magnet carrying frame is 80 pivoted on the cylindrical casing 46.

The magnet carrying frame consists of a bar of suitable magnetic material such as iron, bent intermediate its ends at four points as shown in Fig. 5, so as to provide 85 the two inclined sides 51 and 52 joined by the horizontal top part 53. At the lower ends of the two inclined sides 51 and 52, the bar is bent laterally and outwardly to provide the diaphragm supporting seats 54 and 90 55 located on opposite sides of the frame. Beyond the outer end of the seat 55, the bar is bent downwardly and bifurcated as at 95 56 and 57 to fit on opposite sides of the lug 49, and the bifurcated parts 56 and 57 have 95 holes to receive the ends of the pin 50 whereby the magnet and diaphragm carrying frame are pivotally supported from the casing.

The diaphragm 58 comprises a thin elastic 100 metal plate or reed of magnetic material which has its ends perforated to receive the screws 59 and 60, whereby it is fastened to the seats 54 and 55 on the magnet frame. Intermediate its ends, the diaphragm 58 is 105 gradually contracted from its ends toward the center, and substantially at the center there is a lug 61 which carries the cutting sapphire or stylus 62 which is capable of engaging and producing a record on the rotatable record receiving medium 10.

An electro-magnet 63 having a soft iron core 64, extending beyond each end thereof, is adjustably secured to the inner side of the 110 top part 53 of the magnet frame by a screw 65. One end of the core 64 rests against the inner side of the wall 53 and the other end is disposed in close proximity to the inner side of the diaphragm 58 and on the opposite side thereof from the stylus 62. By the 115 construction of the frame and the connection of the reed armature or diaphragm 58 and core 64 to said frame, I obtain a closed magnetic circuit with but a single air gap, that between the armature 58 and the lower 120 part of the core of the magnet.

When the winding of the electro-magnet 125 63 is deenergized the value of the magnetic flux in the core thereof is substantially *nil*. When this electromagnet is connected to the 130

source of direct current an initial quantity of magnetic flux is established therein.

In order to exclude cylinder shavings and other foreign particles from becoming lodged between the surface of the magnet, core 64 and the inner side of the reed 58, and also to eliminate the metallic sound of the reed armature due to overtones and harmonics we insert a felt washer 66 in the space between the magnet and the diaphragm. The felt washer has a hole 67 capable of fitting the end of the core 64 and is of sufficient thickness to extend slightly beyond the end of the core. The felt washer surrounding the core serves as a damper and while we have adopted felt, it is to be understood that other suitable material may be found which will serve equally well.

In order to compensate for slight variations on the surface of the phonographic record and to provide for all variations and difference in the thickness of records, as, for instance, the difference in thickness of new and reshaved records, I provide a novel means for suspending the free end of the magnet and diaphragm carrying frame on the opposite side thereof from its pivotal support. The outer side of the inclined member 51 of the magnet carrying frame has a hook 68 fixed thereon which, by means of a wire link 69, is flexibly connected to a hook 70 at the outer end of a flat spring plate 71 rigidly connected by the screws 72 to the underside of a counter-weight 73. The counter-weight 73 is a semi-circular plate of material conforming to the shape of the cylindrical casing 46 but of smaller diameter. At its opposite ends, the counter-weight has recesses to receive the pointed ends of threaded pins 74 and 75, whereby the counter-weight is pivoted on the interior of the casing 46 substantially directly above the magnet 63. The pins 74 and 75 pass through threaded holes on diametrically opposite sides of the casing 46 and are provided with the slots 76, whereby they may be adjusted with a screw driver or similar instrument, and by means of the nuts 77 they may be locked in adjusted position. The upper side of the counter-weight 73 has a lug 78 with a threaded opening to receive the threaded shank 79 of an adjusting screw 80, by means of which the effect of the counter-weight may be varied. The nut 81 may serve to lock the adjusting screw in its adjusted position or it may also be used to vary the adjustment of the counter-weight, the counter-weight 73 being cut away intermediate its ends as at 82 to receive the adjusting nut 81. It will be seen that by varying the position of the adjusting screw 80, the effect of the counterbalancing weight 73 may be changed and a very fine adjustment may be obtained. The casing 46 has two binding posts 83 and 84 fixed to the wall

thereof and the shanks of said posts extend through the wall of the casing to provide the binding posts 85 and 86 on the inner side of the casing to which the winding of magnet 63 may be connected. Suitable bushings 87 insulate the binding posts from the walls of the casing. The wire conductor 88 serves to connect the spring contact 41 with the binding post 83 and the wire 89 connects the binding post 84 with one terminal of the transmitter 90 supported on the desk stand 91.

The desk stand 91 also carries a hook 92 which operates a spring switch 93 located between the contacts 94 and 95. The switch 93 is connected by the wire 96 to a battery 97, which latter is connected by a wire 98 to the other switch spring 42 on the underside of the pump cylinder 35. The wire 99 connects the other side of the transmitter 90 to the switch contact 95 and the wire 100 with the wire 99 connects the switch contact 95 and the transmitter 90 to one side of the receiver 101, the other side of the receiver being connected by the wire 102 to a battery 103 which latter is connected by a wire 104 to the other switch contact 94 controlled by the hook 92. When the receiver 101 is on the hook 92 and the recording mechanism has been started by operating the plungers 33 and 37, the transmitter 90 may be used as the ordinary mouth piece of a dictating machine for dictation purposes. The electromagnet 63 will be energized with current by the battery 97 and sound vibrations in the transmitter 90 will operate the diaphragm thereof to create changes in flux density in the magnet 63 which vibrates the diaphragm 58 and stylus 62. The apparatus thus far described is entirely separate from and independent of the commercial telephone company's lines and instruments.

In order to obtain a record of a conversation sent over a telephone line, the special transmitter 90 has been devised which can be used as an ordinary transmitter or is adapted to receive the sound vibrations delivered or emitted by the receiver 105 of a standard desk telephone set. The standard desk telephone set also has the pedestal 106 which supports the usual transmitter 107, and both the transmitter 107 and the receiver 105 are connected to the telephone line comprising the wires 108 and 109.

The special transmitter 90 comprises a casing 110 constituting the diaphragm chamber and containing the usual diaphragm 111 and other working parts, which as herein shown are substantially those of a standard Kellogg transmitter. The type of transmitter working parts is however immaterial. The front of the casing 110 consists of an annular member 111' which is screwed to one end of the sound tube 112 and a mouth piece 114 is screwed into the other end of said 130

tube. The tube 112 forms a sound duct 113 as shown which is substantially tubular and has a tubular lateral connection 115 forming the passageway 116, which opens into the duct 113. At its outer end, the tubular member 115 has a seat 117 provided with a rim flange 118. The seat 117 is circular and the flange 118 confines a felt pad 119 on said seat. The felt pad 119 is annular in shape 5 so as to provide an opening therethrough in line with the inlet opening 120 of the lateral passageway 116. As shown in dotted lines, the felt pad 119 serves to yieldingly support the receiver 105 in such a position that 10 the sound waves emitted from the central opening 121 of the receiver will be delivered directly into and in line with the sound duct 116 and from there will be delivered into the passageway 113 and to the diaphragm 111 15 when the door 122, which controls communication between the passageway 116 and duct 113, is down.

The door or cover 122 is pivoted at a point 123 where the passageway 116 opens into the duct 113 and in such a position that when the door is down, as shown in dotted lines in Fig. 3, it will prevent the entrance of sound from the mouth piece 114 through the duct 113 to the diaphragm chamber but will permit sound entering from the passageway 116 to pass through the duct 113 into the diaphragm chamber, the door being disposed at an angle serves to deflect the sound. The means for raising and lowering the door 30 comprises a button 124, the shank of which is adjustably connected by a set screw 125 to a rod 126, at the lower end of which is a hook 127, a part of which extends into a recess 128 in the underside of the door 122. 35 As will be seen, the rod 126 extends through a hole in the wall of the tube 112 and into the interior of the tube. The spring 129 bearing against the outer surface of the tube 112 and against the lower end of the shank 40 of the button 124 sustains the button and the hook connected thereto in such a position that the door 122 normally closes the entrance of the passageway 116 and prevents communication between the passageway 116 45 and the duct 113. It will be seen that when the receiver 105 is set in position on the bracket formed by the support 117 and tube 115, the end of the button 124 will be engaged and depressed, thus releasing the door 50 which by gravity will swing down into the position shown in dotted lines, closing communication between the mouth piece 114 and the diaphragm chamber and opening communication between the passageway 116 and 55 the duct 113 to the diaphragm chamber. When the receiver 105 is removed, the button and door will be automatically restored to their initial position. The weight of the receiver will keep the plunger, which controls the door, depressed.

When it is desired to record a telephone conversation, the receiver 101 of the isolated station is removed from its switch hook 92 and placed to the ear, the receiver 105 having been previously set on the felt padded 70 bracket. The transmitter 107 of the instrument connected to the telephone company's lines is utilized in the usual manner and conversation may proceed, while at the same time a record of the same is being made 75 upon the cylinder 10. The receiver 101 of the isolated station is of the direct current type and in order to compensate for the increase in ohmic resistance in the recording circuit additional battery current is provided 80 by the battery 103 when the receiver is included in the circuit.

It will be seen from the drawings and the foregoing description, that I have provided a complete telephone station entirely isolated 85 from the commercial telephone company's equipment. I utilize the special transmitter of the isolated station to receive the conversation from the telephone line and also to deliver direct dictation to the phonographic mechanism. When utilizing the transmitter for direct dictation, the receiver 101 remains upon the switch hook 92.

While I have shown and described the invention in detail, it will be apparent that 95 the principles of the invention are susceptible of wider application, and therefore I do not wish to be limited to the exact details disclosed.

Having thus described the invention, what 100 is claimed is:—

1. In an apparatus of the class described, the combination of an electric circuit, a receiving instrument adapted to be connected therewith, said receiving instrument being capable of producing sound, a recording mechanism having an electro-magnet in which the value of the magnetic flux is normally substantially *nil*, a transmitter, a source of direct current, means whereby direct current may be conveyed from said source to said transmitter and said electro-magnet and establish an initial quantity of magnetic flux in the latter, and means whereby sound from said receiving instrument will 110 create action in said transmitter and thereby cause variation in the quantity of magnetic flux in said electro-magnet.

2. In a combined telephone and phonograph, the combination of a telephone line, 120 a telephone receiver in circuit therewith, a phonographic mechanism comprising a record medium, a stylus capable of engaging said medium, a vibratory member capable of vibrating said stylus, an electro-magnet in 125 which the value of the magnet flux is normally substantially *nil* and in magnetic circuit with said vibratory member, a transmitter, a source of direct current, means whereby direct current may be conveyed 130

from said source of said transmitter and said electro-magnet and thereby establish an initial quantity of magnetic flux in said electro-magnet, and means whereby sound vibrations from said telephone receiver will create action in said transmitter and thereby cause variations in the quantity of magnetic flux in said electro-magnet, said vibratory member being capable of responding to said flux variations whereby said stylus will cause a registration to be made upon said record medium.

3. In an apparatus of the class described, the combination of an electrically operated 15 receiving device capable of emitting sound vibrations when operated, a recording mechanism having a vibratory member, a stylus associated with said member, an electro-magnet in which the value of the magnetic 20 flux is normally substantially *nil* and in magnetic circuit with said vibratory member, means whereby said vibratory member is actuated by sound vibrations emitted by said device, said means including a transmitter, a source of direct current, an electrical circuit switch, and a path for conveying direct current from said source through said switch, said transmitter and said electro-magnet whereby an initial quantity of magnetic 25 flux is created in said electro-magnet, and means for associating said receiving device with said transmitter whereby sound vibrations will cause variations in the quantity of magnetic flux in said electro-magnet.

30 4. In an apparatus of the class described, the combination of an electric circuit, a telephone receiver adapted for connection therewith, a phonographic recording device having an electro-magnet in which the value of 35 the magnetic flux is normally substantially *nil*, electric means for operating said device including a transmitter, a source of direct current and a circuit capable of conveying direct current from said source to said transmitter and said electro-magnet whereby an initial quantity of magnetic flux is established in said electro-magnet, and means whereby the operation of said telephone receiver causes the operation of said electric 40 means.

5. In an apparatus of the class described, the combination of a telephone line, a telephone receiver adapted to be connected therewith, a phonographic recording device 45 having an electro-magnet in which the value of the magnetic flux is normally substantially *nil*, electric means for operating said device including a transmitter, a source of direct current and a circuit capable of conveying direct current from said source to said transmitter and said electro-magnet whereby an initial quantity of magnetic flux is established in said electro-magnet, and means whereby sound vibrations delivered 50 by said receiver are caused to operate said

electric means and thereby cause changes to take place in the quantity of magnetic flux in said electro-magnet.

6. In apparatus of the class described, the combination of a recording mechanism comprising a record medium, a stylus capable of engaging said medium, a diaphragm capable of actuating said stylus, an electro-magnet in which the value of the magnetic flux is normally substantially *nil*, said electro-magnet capable of vibrating said diaphragm, a transmitter, a receiver, a circuit switch, a source of direct current, an electric circuit connecting said transmitter, said receiver, said electro-magnet, said source of direct current and said switch whereby an initial quantity of magnetic flux is created in said electro-magnet by said direct current when said switch is operated, a telephone line, a telephone device capable of producing sound, and means for associating said device with said transmitter whereby electrical changes on the telephone line will cause corresponding electrical changes to take place in the electrical circuit connected with said transmitter and said electro-magnet and cause variations in the quantity of magnetic flux, and whereby said diaphragm will vibrate in response to said variations.

7. In an apparatus of the class described, the combination of a recording mechanism comprising a record medium, a stylus capable of engaging said medium, a diaphragm capable of operating said stylus, an electro-magnet in which the value of the magnetic flux is normally substantially *nil* and in magnetic circuit with said diaphragm, a source of direct current supply, a transmitter, a switching device, an electrical circuit including said electro-magnet, said source of direct current, said transmitter and said switching device, said device being capable of directing a flow of direct current from said supply to said transmitter and said electro-magnet, said current creating an initial quantity of magnetic flux in said electro-magnet, a telephone exchange line, a telephone receiver in circuit with said line, and means for associating said receiver with said transmitter whereby electrical changes on the telephone exchange line will cause corresponding changes to take place in the circuit containing said electro-magnet.

8. In an apparatus of the class described, the combination of a recording mechanism including a diaphragm, an electric device for operating said diaphragm, an electric circuit connected to said electric device, a battery, and a telephone transmitter connected with said electric device by said circuit, a telephone receiver, a battery connected to said telephone receiver, means whereby said telephone transmitter may be connected in circuit with said electric de- 125

vice, said means being capable of connecting said receiver with said transmitter and connecting the batteries in series.

9. In an apparatus of the class described, 5 the combination of a telephone instrument comprising a diaphragm, a mouth piece, and a sound duct leading from said mouth piece to said diaphragm, a lateral passageway for sound waves opening into said duct 10 between the mouth piece and the diaphragm, and means for controlling communication between said lateral passageway and said duct.

10. In an apparatus of the class described, 15 the combination of a telephone instrument comprising a diaphragm, a mouth piece, and a sound duct leading from said mouth piece to said diaphragm, a lateral passageway for sound waves opening into said duct, 20 the inlet of said lateral passageway being normally closed, and means adapted to open the inlet of said lateral passageway and prevent the admission of sound waves to said diaphragm from said mouth piece.

25 11. In an apparatus of the class described, the combination of a telephone instrument comprising a diaphragm, a mouth piece, and a sound duct leading from said mouth piece to said diaphragm, a lateral passageway 30 for sound waves opening into said duct between the mouth piece and the diaphragm, a device normally closing the opening of said lateral passageway into said duct, and means whereby said device is adapted to 35 prevent the admission to said diaphragm of sound waves entering through said mouth piece.

12. In an apparatus of the class described, 40 the combination of a telephone instrument comprising a diaphragm, a mouth piece, and a sound duct leading from said mouth piece to said diaphragm, a lateral passageway for sound waves opening into said duct, a device pivoted within said duct and normally 45 closing the inlet opening of said lateral passageway, and means whereby said device is permitted to swing about said pivot into a position to close said duct at the opposite side of the inlet of said lateral 50 passageway from said diaphragm.

13. In an apparatus of the class described, 55 the combination of a telephone instrument comprising a diaphragm, a mouth piece, and a sound duct leading from said mouth piece to said diaphragm, a lateral passageway for sound waves opening into said duct, means for supporting a telephone receiver with its open end over the outer end of said lateral passageway, and a device normally 60 closing the inner end of said lateral passageway, said device being adapted to be actuated by a telephone receiver set in place over the lateral passageway.

14. In an apparatus of the class described, 65 the combination of a telephone instrument

comprising a diaphragm, a mouth piece, and a sound duct leading from said mouth piece to said diaphragm, a lateral passageway for sound waves opening into said duct, a support near the outer end of said lateral passageway, whereby a sound emitting device may rest on said instrument with its outlet in position to deliver sound waves to said lateral passageway, and means controlled by said sound emitting device for 70 opening and closing the entrance of the lateral passageway to said duct and for opening and closing the inlet of sound from said mouth piece to said duct.

15. In an apparatus of the class described, 80 the combination of a telephone instrument comprising a diaphragm, a mouth piece, and a sound duct leading from said mouth piece to said diaphragm, a lateral passageway for sound waves opening into said duct, a 85 padded support near the outer end of said lateral passageway, whereby a sound emitting device may rest on said instrument with its outlet in position to deliver sound waves to said lateral passageway, and a 90 cover for the entrance of said lateral passageway to said duct, said cover being pivoted so as to swing into position to close the duct on the opposite side of said entrance from said diaphragm to prevent the inlet of 95 sound through said mouth piece, and a member engageable by said sound emitting device for controlling the operation of said cover.

16. In an apparatus of the class described, 100 the combination of a telephone transmitter comprising a diaphragm, a diaphragm chamber, a mouth piece, a sound duct connecting the mouth piece with the diaphragm chamber, and a lateral sound passageway 105 opening into said duct, a bracket for supporting a sound producing member in position to deliver sound waves to said lateral passageway, a closure pivoted at the entrance of the lateral passageway into said sound duct and normally closing said entrance, a device engageable by said sound producing member to release said pivoted closure and permit it to swing into position to close the inlet of said duct from said 110 mouth piece, and means for restoring said device and cover to their initial position when the sound producing member is removed from the bracket.

17. In an apparatus of the class described, 115 the combination of a stylus, a diaphragm, an electro-magnet for vibrating said diaphragm, means for pivotally supporting said stylus, diaphragm and electro-magnet, and means for supporting the magnet, stylus and diaphragm at one side of their pivotal support comprising a counter-weight and a spring.

18. In an apparatus of the class described, 120 the combination of a stylus, a diaphragm, 125

- a frame to which the diaphragm is attached, means for pivotally supporting said frame on one side of said stylus, and means for supporting the frame at the opposite side of 5 the stylus comprising a counter-weight.
19. In an apparatus of the class described, the combination of a stylus, a diaphragm, a frame to which the diaphragm is attached, means for pivotally supporting said frame 10 on one side of said stylus, and means for supporting the frame at the opposite side of the stylus comprising a pivoted counter-weight and a spring connected to the counter-weight and to said frame.
- 15 20. In an apparatus of the class described, the combination of a stylus, a diaphragm, a frame carrying said stylus and diaphragm, means for pivotally supporting said frame at one side of said stylus, and 20 means for yieldingly supporting said frame at the side opposite from the pivotal support, said means comprising a counter-weight pivoted above the frame, a flat spring plate secured to said counter-weight 25 and connected to said frame, and means for adjusting the counter-balancing effect of the counter-weight.
21. In an apparatus of the class described, the combination of a stylus, a diaphragm, 30 a frame supporting said stylus and diaphragm, means for pivotally supporting said frame on one side of said stylus, a casing inclosing part of said frame, a counter-weight pivoted within said casing, and 35 means for connecting said counter-weight to a part of said frame opposite the pivotal support of the latter.
22. In an apparatus of the class described, the combination of a diaphragm, a phono- 40
- graphic stylus connected therewith, a magnet for vibrating said diaphragm and stylus, and a washer located between the magnet and diaphragm to prevent accumulations of foreign particles between the adjacent surface of the magnet and diaphragm and to 45 eliminate the sound of the diaphragm.
23. In an apparatus of the class described, the combination of a diaphragm, a phonographic stylus connected therewith, an electro-magnet for vibrating said diaphragm 50 and stylus, said magnet having a central core, and a felt washer located between the diaphragm and the electro-magnet and surrounding the magnet core, for the purposes set forth. 55
24. In an apparatus of the class described, the combination of a phonographic record medium, rotating means therefor, a stylus capable of engaging said medium, a diaphragm capable of operating said stylus, 60 and an electro-magnet in which the value of the magnetic flux is normally substantially *nil* associated with said diaphragm, an electrical circuit containing a transmitter, a circuit switch, a source of direct current, 65 and means for controlling said rotating means and simultaneously closing said circuit switch so direct current may flow through both the transmitter and electro-magnet and thereby establish an initial 70 quantity of magnetic flux in said electro-magnet.

In testimony whereof I affix my signature in presence of two witnesses.

JOHN F. MALTHANER.

Witnesses:

C. J. YANCEY,
EVELYN RODDY.
